CLAIM

I claim the ornamental design for a kettle with base, as shown and described.

DESCRIPTION

FIG. 1 is a front perspective view of a kettle with base;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The ornamental design which is claimed is shown in solid lines in the drawings. The broken lines show portions of the kettle with base that form no part of the claimed design.

1 Claim, 7 Drawing Sheets
